UNITED STATES PATENT OFFICE.

JOHN E. MUHLFELD, OF SCARSDALE, NEW YORK, ASSIGNOR TO LOCOMOTIVE PULVERIZED FUEL COMPANY, A CORPORATION OF DELAWARE.

APPARATUS FOR FEEDING PULVERIZED FUEL.

1,282,106.

Specification of Letters Patent. Patented Oct. 22, 1918.

Application filed December 31, 1913. Serial No. 809,697.

To all whom it may concern:

Be it known that I, JOHN E. MUHLFELD, of Scarsdale, in the county of Westchester and State of New York, have invented a certain new and useful Improvement in Apparatus for Feeding Pulverized Fuel, of which improvement the following is a specification.

My invention relates to means for delivering pulverized fuel from a storage receptacle to one or more supply conduits, through which it is conveyed to a desired point of delivery, and its object is to provide an apparatus of such character which shall be of simple and inexpensive construction and ready applicability, and by which a continuous supply of pulverized fuel may be maintained, in desired and determined quantity, and any excess above such quantity which may be taken up by the feeding mechanism will be returned to the storage receptacle.

The improvement claimed is hereinafter fully set forth.

In the accompanying drawings: Figure 1 is a vertical section through an apparatus for feeding pulverized fuel, illustrating an embodiment of my invention; Fig. 2, a transverse section through the same, on the line *a a* of Fig. 1; Fig. 3, a section, similar to Fig. 1, showing a structural modification; Fig. 4, a transverse section through the same, on the line *b b* of Fig. 3; Fig. 5, a similar section, on the line *c c* of Fig. 1; and, Fig. 6, a partial section, showing a further structural modification.

My invention is herein exemplified as applied in connection with a pulverized fuel storage receptacle, which may be of any desired form and dimensions, and which, not being, in and of itself, of my present invention, is not herein shown. Referring first to Figs. 1 and 2, in the practice of my invention, I provide, for connection to the lower portion of a fuel receptacle, one or more conveyer channels or casings, 1^a, any desired number of which may be applied, and three being shown in this instance, said channels being open, through suitable inlets at or near their receiving ends to a fuel storage receptacle. A discharge opening, 1^b, is formed in the bottom of each of the conveyer channels, and a rotatable feeding conveyer, is fitted to operate above the discharge opening in such manner as to carry pulverized fuel to said opening. The feeding conveyer is of the

screw type, and comprises a helical blade, 2, which is formed upon or secured to a hollow or tubular shaft, 2^a, journaled in bearings, 11, in the opposite ends of the conveyer channel, the bearing at the right hand end only being shown in the drawings. Upon rotation being imparted to the conveyer, in any suitable manner, pulverized fuel from the storage receptacle, which drops by gravity into the conveyer channel, will be moved longitudinally, in the latter, and carried to the discharge opening, 1^b, thereof.

A measuring wheel, 3, the periphery of which is divided into a plurality of transverse grooves or recesses, 3^a, is secured upon a shaft, 4, which is mounted in bearings, 5^a, on a casing, 5, within which the measuring wheel rotates and fits comparatively closely. The shaft, 4, may be rotated as found most suitable under conditions of installation. A delivery conduit, 6, located below the casing, 5, communicates therewith through an opening, 6^a, in its top, located immediately below the measuring wheel, 3, and leads to a desired point of delivery, as a boiler furnace, 80 the lower end of the water space of which is shown at A, in Figs. 1 and 3. It will be seen that a measured quantity of pulverized fuel will be carried from the conveyer channel to the delivery conduit, in each revolution of the measuring wheel, its quantity being dependent upon the width of face of said wheel, and the depth of its peripheral grooves, and as a surplus of pulverized fuel is carried over the discharge opening by the conveyer, the delivery of a measured quantity of pulverized fuel is insured. While only one discharge opening and one measuring wheel are shown in connection with a conveyer channel, two or more may be applied, in the discretion of the constructor, the number thereof being principally dependent upon the length of the conveyer channels and the desired rapidity of feed of the fuel.

In order to carry back to the receiving end of the conveyer channel, any quantity of fuel which is in excess of that which is discharged therefrom by the measuring wheel, 3, and which, consequently, is carried by the conveyer blade, 2, beyond the discharge opening, 1^b, a return conveyer is mounted within the tubular shaft, 2^a, of the feeding conveyer, in which longitudinal openings, 2^b, are formed, adjacent to its discharge end.

The return conveyer comprises a helical blade, 22, and a shaft, 22^a, on which said blade is formed or fixed. As shown in the drawings, the blades of both the feeding and return conveyers lead in the same direction, i. e., both are right handed screws, and, in such case, the return conveyer is rotated by appropriate driving means, in opposite direction to the feeding conveyer, and the return conveyer shaft, 22^a, is therefore mounted in independent central bearings, 11^a, in the bearings, 11, of the feeding conveyer. The feeding and return conveyer blades may, however, if preferred, be of opposite leads, i. e. one a right handed and the other a left handed screw, and in such case may be rotated in the same direction by a single driving mechanism. The feeding conveyer shaft is provided with longitudinal wings or vanes, 2^a, located between the openings, 2^c, said wings or vanes serving to gather up the surplus fuel and carry it, through said openings, to the blade of the return conveyer.

The space within the conveyer channel between the bearing, 11, and the adjacent end of the channel may be utilized for containing lubricating material and protecting the bearing from the heat of the furnace, or for the reception of means for rotating the conveyers.

Figs. 3 and 4 illustrate a structural modification embodying the essential operative principle of the apparatus above described, and differing structurally therefrom in the particular that the shafts of the measuring wheels, 3, three of which are shown on each shaft, in this instance, are located, in the same vertical planes as, and parallel with, the conveyer shafts, 2^a, 22^a, instead of being set at a right angle thereto, as in the former case. The shafts of the measuring wheels may, as shown, be rotated by spur gears, 4^a, fixed thereon and engaging similar gears, 2^b, on the conveyer shafts.

As shown in Fig. 6, the shafts of the measuring wheels are located relatively to the conveyer shafts similarly to those of Figs. 3 and 4, but all the measuring wheels of each conveyer channel discharge into a single delivery conduit, instead of into independent conduits as in Figs. 2, 3, and 4.

The fuel feeding apparatus above described may be varied as to form, dimensions, and number of elements of each conveyer channel or casing provided for the fuel storage receptacle, in accordance with operative conditions and installation requirements, without departure from the spirit and characteristic features of my invention.

I claim as my invention and desire to secure by Letters Patent:

1. In an apparatus for feeding pulverized fuel, the combination, with a fuel conveyer channel having a lower discharge opening, of a fuel delivery conduit extending below said opening, means for conveying fuel through the channel to and across said opening, means for transferring fuel, in measured quantities, from said opening to the fuel delivery conduit, and means for returning untransferred fuel, through said transferring means, to the receiving inlet of the conveyer channel.

2. In an apparatus for feeding pulverized fuel, the combination, with a fuel conveyer channel having a lower discharge opening, of a fuel delivery conduit extending below said opening, a conveyer rotatable in said channel for conveying fuel to said opening, means for transferring fuel, in measured quantities, from said opening to the fuel delivery conduit, and a conveyer rotatable within said first specified conveyer, for returning untransferred fuel to the receiving inlet thereof.

3. In an apparatus for feeding pulverized fuel, the combination, with a fuel conveyer conduit having a receiving opening and a lower discharge outlet, of a fuel delivery conduit extending below said outlet, means within said conveyer conduit for conveying fuel therethrough to and across said outlet, means for transferring fuel in measured quantities from said outlet to the fuel delivery conduit, and a second means within said conveyer conduit for returning untransferred fuel to the receiving opening.

JOHN E. MUHLFELD.
